[57] CLAIM

We claim the ornamental design for a bottle body portion, as shown and described.

DESCRIPTION

FIG. 1 is a perspective view of a bottle body portion showing our new design.

FIG. 2 is a front view thereof.

FIG. 3 is a rear view thereof.

FIG. 4 is a side view thereof.

FIG. 5 is a top view thereof; and,

FIG. 6 is a bottom view thereof.

The unshown side of the bottle body portion is a mirror image of the side shown in FIG. 4.

The broken lines in the drawings are for illustrative purposes only and do not form part of the claimed design.
